CATHODE-RAY TUBE FOR THE REPRODUCTION OF COLOUR TELEVISION IMAGES

Johannes De Gier, Eindhoven, Netherlands, assignor, by mesme assignments, to North American Philips Company, Inc., New York, N. Y., a corporation of Delaware

Application April 27, 1956, Serial No. 581,109

Claims priority, application Netherlands May 12, 1955

8 Claims. (Cl. 315—13)

The invention relates to cathode-ray tubes and apparatus for the reproduction of coloured television images in which the tube contains at least two electron guns.

For the reproduction of coloured television images by means of a single cathode-ray tube widely different tube constructions have been suggested. Inter alia, a cathode-ray tube has been described having three electron guns by means of which three concentrated electron beams can be directed to an image screen containing three luminescent substances emitting light of different colours, which substances are arranged uniformly in discrete surfaces and, in the operation of the tube, can each be excited by a beam from a single electron gun. In order to build up the image, a predetermined signal is supplied to each of the guns. It has been described that it is not necessary to supply signals of the same bandwidth to the three guns, for, in order to ensure the production of a satisfactory coloured image, it is sufficient that one of the coloured images has a high definition and consequently it suffices when a signal of large bandwidth is supplied to the electron gun for this colour. Thus, this gun determines the definition of the image. In most systems in present use the three primary colours chosen are red, green and blue, and for visual observation it has proved to be of advantage to determine the definition by means of the green image. However, for special purposes the definition may be determined by any of the other primary colours. The blue image will, for example, be used, when use is made of an image amplifier connected after the colour tube, which amplifier has a maximum sensitivity in the blue region.

Although it has not been described, it will be obvious that what has been written hereinbefore with respect to the bandwidth also applies to the case where two or more than three electron guns and a corresponding number of primary colours are used.

The use of the different bandwidth was discovered in the search for a composite television signal which is suitable for wireless transmission and does not have an excessively large over-all bandwidth, preferably a bandwidth not exceeding that of a signal of the kind used in black-and-white television.

In a cathode-ray tube in accordance with the invention the construction of the electron guns has been made to conform with the insight gained into the required bandwidth, with resulting advantages which will be described more fully hereinafter.

A cathode-ray tube in accordance with the invention for the reproduction of coloured television images comprises an image screen provided with at least two luminescent materials, which, on electron bombardment, emit light of different colours and with different efficiency and are arranged in discrete uniformly distributed surfaces, and at least two electron guns, which each comprise at least a cathode, a control grid and an anode and which generate electron beams which each pass through a principal or main focussing lens having the same image

2

ratio and each co-operate with luminescent material emitting light of one colour only, the control electrode of the gun which cooperates with a luminescent material of higher efficiency having a signal supplied to it which has a greater bandwidth than the signal supplied to the control electrode of the gun co-operating with a luminescent material of lower efficiency. The geometry of the tube is such that the spot size of the gun co-operating with luminescent material of higher efficiency at a predetermined current strength and with maximum focusing by the principal lens is smaller than that of the gun co-operating with a luminescent material of lower efficiency, when compared under conditions of the same current strength and with maximum focusing.

15 The term "image ratio of the principal lens" as used herein is to be understood to mean the ratio between the distance by which the infinitely thin lens, which with respect to its effect may replace the principal lens, is spaced away from the image screen and the distance by 20 which it is spaced away from the control electrode. This image ratio is analogous to the image ratio of an optical lens. In actual fact, the object, an image of which is produced electron-optically, is the cross-over produced in close proximity to the control electrode. In practice 25 it is immaterial whether use is made of the distance between the principal lens and the cross-over or of the distance between the principal lens and the control electrode. However, the latter distance can more readily be measured in the tube.

30 Since the image ratios of the principal lenses are equal for the various electron guns and the focusing is adjusted to have its maximum value, a larger beam spot on the image screen means that the cross-over also is 35 larger, for the cross-over is the object of which an image is produced by the principal lens. A larger cross-over means a smaller specific cathode load, i. e. the current per sq. cm. of the operative cathode surface. From this it follows that in a cathode-ray tube in accordance with the invention, the specific cathode loads of all the electron 40 guns approximate to one another as closely as possible. This can be explained as follows:

The luminescent material with which the gun for the greater bandwidth co-operates, requires a certain current strength to produce a predetermined amount of light. In 45 order to ensure that the luminescent material of smaller efficiency, which consequently is excited by the electron beam of a gun to which a signal of smaller bandwidth is supplied, produces an amount of light which matches the first-mentioned amount of light, a greater current strength in the electron beam is necessary. If the size 50 of the beam spot on this luminescent material were made equal to that on the luminescent material of higher efficiency, there would be, for a cross-over of equal surface area, a greater current strength, and this means that 55 the specific cathode load of the gun producing this cross-over is greater. Since the specific cathode load determines the lifetime of the cathode, the life of the last-mentioned cathode would be shorter than that of the first-mentioned cathode. It is obvious that this is very 60 inconvenient, since the guns and consequently the cathodes are arranged in one tube and hence failure of one cathode necessitates replacement of the tube or viewing pictures in unnatural colours henceforth.

65 However, as has been described hereinbefore, it is not necessary that the definition of all the images be equal and hence when the higher definition is produced in the screen of the highest efficiency, the spot on the screen material of smaller efficiency can be made larger. As has been explained hereinbefore, this results in a smaller specific cathode load in the gun which co-operates with the luminescent material of lower efficiency. Although in

some cases the specific cathode loads cannot be made exactly equal in this manner, the longest possible lifetime will thus be obtained for all the cathodes.

Since the size of the cross-over is also dependent upon the value of the current in the electron beam, any comparison of beam spot sizes must obviously be made with the same current strength. In the operation of a tube in accordance with the invention, the current in the electron beam produced by the gun which co-operates with the luminescent material of lower efficiency will exceed the current in the beam of the gun which co-operates with the luminescent material of higher efficiency.

At a predetermined value of the current strength, a larger cross-over and consequently a larger spot can, for example, be obtained by a larger aperture of passage in the control electrode and by a larger spacing between the cathode and the control electrode. Consequently, variations in the geometry of the electron gun permit of obtaining a predetermined size of the cross-over and consequently of the spot on the image screen, at a given current strength.

A larger aperture of passage of a control electrode results in the reduction of the so-called cut-off voltage, i. e. the voltage of the control electrode at which the electron beam current is reduced to zero. By the choice of the cathode-control electrode spacing, the cut-off voltages can be made substantially equal for the various guns. Thus, a complicated circuit arrangement is avoided, which would be required, if use were made of guns having different cut-off voltages.

In many cases it will be necessary to arrange in front of the image screen a mask electrode, which ensures that electrons from one gun can excite luminescent material only which emits light of one colour. If required, the electron beams may be additionally concentrated in known manner between the mask and the image screen. In this embodiment, the spot size must be measured at the mask.

The electron beams produced by the guns can be passed through a common principal lens. By ensuring that in all the guns the cathode is spaced away from the principal lens by the same distance, it can be ensured that the image ratio is the same for all the guns.

The invention will now be described more fully with reference to a practical embodiment, given by way of example, of a cathode-ray tube for visual observation, in which use is made of 3 luminescent materials, which emit green, red and blue light respectively. As luminescent materials use was made for the green image of willemite, for the red image of zinc beryllium silicate activated with manganese, and for the blue image of calcium magnesium silicate activated with titanium. Of the said three substances, the willemite has the highest efficiency. Since the tube is to be used for visual observation, it is of advantage to determine the definition by the green image. Consequently, the spot on the material luminescent in green must be smallest. Since, in measuring, a raster was traced out, the line width was measured instead of the spot size, which amounts to the same thing.

With a line width of 0.033 mm., a well-defined green image was obtained with a current strength of 90 micro-amperes. The specific cathode load of the corresponding electron gun was 0.146 amp./sq. cm.

In order to obtain an image having a brightness matching the brightness of the green image, with the same line-width, on the material luminescent in red a current strength of 200 micro-amps. was required. The specific cathode load of the corresponding gun in this case would be 0.28 amp./sq. cm. It was found that the linewidth on the material luminescent in red could be enlarged to 0.065 mm. without the image produced by the combination of the images being seriously affected. However, to obtain satisfactory brightness, the current strength has to remain 200 micro-amps. The specific cathode load of the gun for the red image, however, was reduced to 0.19

amp./sq. cm., only slightly larger than that of the green gun.

With a same linewidth as measured on the screen luminescent in green, on the material luminescent in blue a current strength in the electron beam of 120 micro-amps. was found for an image having a brightness matching that of the green and red images. The specific cathode load of the corresponding gun in this case was 0.174 amp./sq. cm. It was found that the line width on the material luminescent in blue could be enlarged to 0.065 mm. without the combination picture being affected. With the same current strength of 120 micro-amps., the specific cathode load was reduced to 0.126 amp./sq. cm.

The diameter of the area of passage of the control electrode was 0.5 mm. in the electron gun for the green image and 0.6 mm. in the two other electron guns.

The cut-off voltages were equal for all the three guns, i. e. 60 volts. In the electron gun for the green image the spacing between the control electrode and the cathode was 0.2 mm. and in the two other guns 0.25 mm. The thickness of the control electrode and the spacings between the said electrode and the screen were equal in all the electrode systems.

The invention will now be described more fully with reference to the accompanying drawing, of which the single view is a partly schematic, partly cross-sectional view of cathode-ray tube apparatus according to the invention.

In the drawing, the cathode-ray tube shown consists of a cylindrical neck portion 1 and a mating conical part 2 closed off by a transparent window 3. This window supports a luminescent screen 4 containing three luminescent materials, luminescing in three primary colors, arranged in a repetitive pattern. In the neck 1 of the tube, three electron guns are arranged, in which the two outer electron guns are identical. These two guns comprise a cathode 5, a diaphragm 6 acting as a control grid, an accelerating or first anode 7 and a final anode 8. Due to the cooperation of the electrodes 5, 6 and 7, which serve as an immersion or first lens, a cross-over is produced approximately in the aperture of the control grid 6. This node is projected onto the luminescent screen 4 by means of a second electron lens formed by a focussing coil 9, which lens is called the main or principal lens. This main lens is as may be seen common to the cathode-rays produced by the three guns. Apart from focussing each electron beam, this main lens at the same time converges the three beams to a common point 15 of the image screen 4. Between the main lens formed by the coil 9 and the screen the three electron beams are deflected with the aid of deflecting coils 13 and 14.

As will be seen from the drawing, the central gun is of a construction which is for the greater part similar to the construction of the two outer guns. However, in the central gun, the aperture or passage in the control grid 6 is smaller than the corresponding apertures in the control grids of the two outer guns. Moreover, the distance between the cathode and the control-grid is smaller for the central gun than for the two outer guns. As shown in the drawing, three signal sources are provided for applying signals of bandwidth A and a signal of larger bandwidth $A + \Delta A$ to the control grids 6 of the three guns for modulating their beam current. In accordance with what is described above, the signal with the greater bandwidth $A + \Delta A$ is applied to the central gun. This central gun, which produces a smaller beam spot, co-operates with the luminescent material of higher efficiency on the screen 4.

What is claimed is:

1. A cathode-ray tube comprising an image screen containing plural luminescent materials possessing higher and lower efficiencies and luminescing in plural colors to form a composite color image, and a plurality of electron guns each producing an electron beam for exciting one of said luminescent materials, said gun exciting the higher-

efficiency luminescent material producing a smaller beam spot size in the vicinity of the screen than that of the other guns, when compared under conditions of the same beam current and the same beam focussing.

2. A tube as set forth in claim 1 wherein each of the guns includes a cathode and an apertured control grid, the control grid of the gun exciting the higher-efficiency luminescent material having a smaller aperture than that of the control grids of the other guns.

3. A tube as set forth in claim 1 wherein each of the guns includes a cathode and an apertured control grid, the spacing between the cathode and the control grid of the gun exciting the higher-efficiency luminescent material being smaller than that of the other guns.

4. Cathode-ray tube apparatus comprising: a cathode-ray tube having an image screen containing plural luminescent materials possessing higher and lower efficiencies and luminescing in plural colors to form a composite color image, and a plurality of electron guns each including cathode and apertured control grid electrodes and each producing an electron beam for exciting one of said luminescent materials; and a principal lens associated with the guns and having the same image ratio for each of the guns for focussing the beams onto the image screen; said gun exciting said higher-efficiency luminescent material producing a smaller beam spot size in the vicinity of the screen than that of the other guns, when compared under conditions of equal beam current and maximum focussing by the principal lens.

5. Apparatus as set forth in claim 4 wherein, in the gun exciting the higher-efficiency luminescent material, the aperture in the control grid is smaller than, and the cathode-control grid spacing is smaller than, the corresponding values for the other guns.

6. Cathode-ray tube apparatus comprising: a cathode-ray tube having an image screen containing plural luminescent materials possessing higher and lower efficiencies and luminescing in plural colors to form a composite color image, and a plurality of electron guns each including cathode and apertured control grid electrodes and each producing an electron beam for exciting one of said luminescent materials; a principal lens associated with the guns and having the same image ratio for each of the guns for

10 focussing the beams onto the image screen; said gun exciting said higher-efficiency luminescent material producing a smaller beam spot size in the vicinity of the screen than that of the other guns, when compared under conditions of equal beam current and maximum focussing by 15 the principal lens; plural signal sources generating signals of larger and smaller bandwidth; and means for applying the larger bandwidth signal to the gun exciting the higher-efficiency material and the signals of smaller bandwidth to the other guns.

20 7. Apparatus as set forth in claim 6 wherein, in the gun exciting the higher-efficiency luminescent material, the aperture in the control grid is smaller than, and the cathode-control grid spacing is smaller than, the corresponding values for the other guns, said values being 25 such that the beams of all the guns are cut-off by the same voltage.

8. Apparatus as set forth in claim 6, wherein a common principal lens is provided for all the guns, and the cathode-principal lens spacing is the same for all the guns.
